UNITED STATES PATENT OFFICE

2,455,451

CONDYLE POSITION INDICATING APPARATUS

Charles F. Tully, San Diego, Calif.

Application August 5, 1946, Serial No. 688,561

6 Claims. (Cl. 33—174)

1 My invention relates to a condyle position indicating apparatus, more particularly an improvement over my former patent application, Serial No. 618,025, filed September 22, 1945, and the objects of my invention are:

First, to provide a condyle position indicating apparatus of this class which accurately indicates dimensional movement of a patient's jaws with respect to the vertical axis of said patient when in upright position;

Second, to provide a condyle position indicating apparatus of this class which presents measurements visible to the dental surgeon which indicate certain dimensions required in reproducing a natural condition when fitting the patient with new dentures;

Third, to provide a condyle position indicating apparatus of this class which indicates the amplitude of the bite of a patient substantially perpendicular to the axis of the patient's jaws;

Fourth, to provide an apparatus of this class which promotes the most exacting dimensional reproduction of dentures for a particular patient;

Fifth, to provide a condyle position indicating apparatus of this class which is very quickly and easily applied to the patient for taking a measurement of the patient's jaw positions; and

Sixth, to provide a condyle position indicating apparatus of this class which is very simple and economical of construction, efficient in operation and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon, forming a part of this application, in which:

Figure 1 is a side elevational view of my condyle position indicating apparatus shown in connection with a patient illustrated by dash lines and Fig. 2 is an enlarged sectional view taken from the line 2—2 of Fig. 1 showing parts and portions in elevation to facilitate the illustration.

Similar characters of reference refer to similar parts and portions throughout the views of the drawing.

The head bands 1 and 2, arms 3, chin plate 4, chin plate screw 5, scale member 6, scale guide 7, clamp 8, and the clip 9 constitute the principal parts and portions of my condyle position indicating apparatus.

2 The head bands 1 and 2 are arranged in perpendicular relationship to each other, as shown in Fig. 1 of the drawings. The head band 1, passing over the patient's head laterally thereof, is secured to the head band 2 which passes around the patient's head at forehead elevation as shown best in Fig. 1 of the drawings. The head band 1 extends downwardly and is provided with a pivotal bearing pin 1a on which the normally rear end of the arm 3 is positioned and this bearing pin 1a is arranged at substantially the pivotal axis of the patient's jaws. Adjustably connected with the arms 3, is the chin plate 4 adjustably mounted in connection with the screw 5, all as shown best in Fig. 1 of the drawings.

It will be here noted that the head bands 1 and 2, arms 3, chin plate 4, and adjustment screw 5 are shown in my former patent application, Serial No. 618,025, filed September 22, 1945. The scaled guide 7 is a hollow tubular member open at opposite ends and having a bearing portion 7a at its normally upper ends secured to the clip 9 which is frictionally secured to the head band 2 when in operative position. The scale member 6 is reciprocably mounted in the bore 7b of the scale guide 7 and is provided with graduated portions 6a thereon which may be viewed through the longitudinally slotted portion 7c of the scale guide 7, all as shown best in Fig. 2 of the drawings.

30 It will be noted that the normally upper end of the scale guide 7 is pivotally mounted on the pin 7a and that the normally lower end portion 6b of the scale member 6 is pivotally mounted on the pin 6c in connection with the clamp 8 secured to the arm 3, all as shown best in Fig. 2 of the drawings.

The operation of my condyle position indicating apparatus is substantially as follows:

35 The head band 2 is maintained in secure position on the patient in its connected relation with the head band 1 which passes over the upper portion of the patient's head. The arm 3 is freely pivotal on the bearing pin 1a and is moved by the patient's jaws in connection with the chin plate 4. As the patient's jaws are moved upwardly and downwardly, the scale member 6 moves reciprocally in the bore portion 7b of the scale guide 7. A reading pointer 7d in connection with the scale guide 7, at its slotted portion 7c is used in cooperation with the graduated scale 6a of the scale member 6 for indicating amplitude of the bite made by the patient's jaws when making a measurement thereof. In this manner accurate measurements may be made of the bite of a patient's jaws and various positions thereof so that the

dental surgeon and dental technician may properly fit the patient with new dentures which very accurately conform to the particular dimensions and operation of the patient's jaws.

Though I have shown and described a particular construction, combination, and arrangement of parts and portions, I do not wish to be limited to the particular construction, combination and arrangement, but desire to include in the scope of my invention, the construction, combination and arrangement substantially as set forth in the appended claims.

Having thus described my invention, what I claim as new and desire to secure by Letters Patent is:

1. In a condyle position indicating apparatus, the combination of means adapted to be secured in connection with a patient's head having a pivotal bearing portion substantially aligning with the pivotal axis of the patient's jaw, an arm pivotally connected with said pivotal bearing and extending forwardly toward the chin portion of the patient, reciprocable scale means interconnecting said means and said pivoted arm forwardly of said pivotal bearing to which said pivoted arm is connected for indicating relative dimensional movement of a patient's jaw relatively to his skull.

2. In a condyle position indicating apparatus of the class described, the combination of head engaging means adapted to be securely positioned on the head of a patient having bearing means substantially aligning with the pivotal axis of a patient's jaws when in position on a patient's head, reciprocable scale means in connection with said head engaging means forwardly of said bearing portion, an arm pivotally connected with said bearing portion and extending forwardly in spaced relation to the connection of said reciprocable scale means with said head engaging means, said reciprocable scale means interconnecting said pivoted arm and said head engaging means.

3. In a condyle position indicating apparatus of the class described, the combination of head band means adapted to engage the head of a patient and arranged to extend over the top thereof and around the upper portion of a patient's head and having a bearing portion substantially aligning with the pivotal axis of a patient's jaws, a pivoted arm pivotally connected to said bearing portion of said head band means and extending forwardly toward the chin of a patient wearing said head band means, and reciprocable scale means interconnecting said head band means and said pivoted arm forwardly of the pivotal axis of said pivoted arm.

4. In a condyle position indicating apparatus of the class described, the combination of head band means adapted to engage the head of a patient and arranged to extend over the top thereof and around the upper portion of a pa-

tient's head and having a bearing portion substantially aligning with the pivotal axis of a patient's jaws, a pivoted arm pivotally connected to said bearing portion of said head band means and extending forwardly toward the chin of a patient wearing said head band means, and reciprocable scale means interconnecting said head band means and said pivoted arm forwardly of the pivotal axis of said pivoted arm, said reciprocable scale means pivotally connected with said head band means and said pivoted arm at its opposite ends.

5. In a condyle position indicating apparatus of the class described, the combination of head band means adapted to engage the head of a patient and arranged to extend over the top thereof and around the upper portion of a patient's head and having a bearing portion substantially aligning with the pivotal axis of a patient's jaws, a pivoted arm pivotally connected to said bearing portion of said head band means and extending forwardly toward the chin of a patient wearing said head band means, and reciprocable scale means interconnecting said head band means and said pivoted arm forwardly of the pivotal axis of said pivoted arm, said reciprocable scale means pivotally connected with said head band means and said pivoted arm at its opposite ends, said reciprocal scale including a tubular member and a scale member reciprocally mounted therein.

6. In a condyle position indicating apparatus of the class described, the combination of head band means adapted to engage the head of a patient and arranged to extend over the top thereof and around the upper portion of a patient's head and having a bearing portion substantially aligning with the pivotal axis of a patient's jaws, a pivoted arm pivotally connected to said bearing portion of said head band means and extending forwardly toward the chin of a patient wearing said head band means, and reciprocable scale means interconnecting said head band means and said pivoted arm forwardly of the pivotal axis of said pivoted arm, said reciprocal scale means pivotally connected with said head band means and said pivoted arm at its opposite ends, said reciprocal scale including a tubular member and a scale member reciprocally mounted therein, said tubular member having a longitudinally slotted portion therein through which said scale member may be read.
